(57) CLAIM

We claim the ornamental design for a golf grip collar, as shown and described.

DESCRIPTION

FIG. 1 is a perspective view of the golf grip collar

FIG. 2 is a side view of the golf grip collar

FIG. 3 is a top view of the golf grip collar

FIG. 4 is a bottom view of the golf grip collar; and,

FIG. 5 is a view of the golf grip collar attached to a golf club shaft.

The broken line showing of the golf grip and fragmented shaft is included for the purpose of illustrating and forms no part of the claimed design.
